UNITED STATES PATENT OFFICE.

HUBERT C. VERHEY, OF OCEAN CITY, NEW JERSEY.

INTERNAL-COMBUSTION ENGINE.

Application filed March 31, 1920. Serial No. 370,076.

To all whom it may concern:

Be it known that I, HUBERT C. VERHEY, a citizen of the United States, residing at Ocean City, in the county of Cape May and State of New Jersey, have invented certain new and useful Improvements in Internal-Combustion Engines, of which the following is a specification.

My invention relates to improvements in internal combustion engines and particularly to oil burning engines known as the Diesel type of engines.

The main object of my invention is to make various improvements in the cylinder construction of the engine to overcome the difficulties heretofore experienced in constructing a cylinder which will withstand the heat of combustion without cracking; a further object of my invention is to provide a novel form of cylinder liner, which will be free to expand and contract, at the main working end of the cylinder, due to extreme changes in temperature; a further object of my invention is to construct a cylinder head having novel means for securing it to the cylinder casing or cooling jacket, which construction will permit the cylinder head, and also the cylinder liner, to have radial flexibility, while transmitting the load, applied at the main working end of the cylinder, to the cylinder casing or cooling jacket; a still further object of my invention is to provide means for insuring the register of the cylinder liner and the cylinder head upon the said casing, instead of on the cylinder liner as heretofore applied; a still further object of my invention is to construct the cylinder head with a novel form of cooling arrangement for directing the cooling agent to the hottest part of the cylinder head first and for insuring the proper distribution of the cooling agent throughout the cylinder head cooling chamber, by constructing the cylinder head with a dome shaped surface tending to improve the circulation therein and by guiding the cooling agent towards the outlet, or outlets, formed in the top of the cylinder head cooling chamber; a still further object of my invention is to construct the cylinder head with the various valve-cage bosses extending parallel with the length of the cylinder and extending in line with the direction of forces applied by the working load in the cylinder against the cylinder head

disk, which load tends to hold said bosses under compression; a still further object of my invention is to provide the cylinder liner with an individual cooling jacket at the working end thereof, which will extend as close as possible to the said working end and thus insure free and unobstructed circulation of the cooling agent around the hottest part of the liner; and a still further object of my invention is to provide a cylinder casing or cooling jacket, particularly adapted for transmitting the working load from the cylinder head to the engine frame, by providing connections or bosses to reinforce the said casing at the exhaust gas duct, which bosses are cored and utilized as connecting passageways for the cooling agent and add to the proper circulation of the cooling agent.

Referring to the accompanying drawing, Fig. 1, is a central vertical section of an engine cylinder and the fuel valve sleeve and cooling agent conveyer, as on line 1—1, Fig. 4; Fig. 2, is a vertical section of my improved cylinder, showing the cylinder liner partially in full lines, as on line 2—2, Fig. 3; Fig. 3, is a horizontal section through the cylinder head and fuel valve sleeve and cooling agent conveyer, as on line 3—3, Fig. 2; Fig. 4, is a horizontal section on line 4—4, Fig. 1; Fig. 5, is an enlarged horizontal section of the fuel valve sleeve and cooling agent conveyer, as on line 5—5, Fig. 1; Fig. 6, is a plan view of the cylinder head with the fuel valve sleeve and cooling water conveyer removed; and Fig. 7, is a horizontal section of the cylinder liner detached, as on line 7—7, Fig. 2.

Referring to the drawings in which like reference characters refer to like parts, 1 represents the cylinder of an engine and comprises the cylinder casing 2, the cylinder head 3 and the cylinder liner 4.

The cylinder casing 2 forms a supporting member for the cylinder head 3 and the liner 4. When used on a vertical engine the casing 2 is supported upon a frame 5, only a portion of which is shown in the drawings. The casing 2, forms a water jacket with a cooling chamber 7 surrounding the cylinder liner 4, and said casing 2 has an exhaust manifold 8 included therein which embraces the central portion of the liner 4 having the exhaust ports 9 formed through the said liner 4. The casing 2 con-

sists of the outer wall 10 which is provided at its ends with facing flanges 12 and 13. The facing flange 12 is provided for securing the casing 2 to the frame 5, and the 5 facing flange 13 is provided for securing the cylinder head 3 to the casing 2 and for clamping the liner 4 in position.

The working end of the cylinder liner 4 which is the upper end, as shown in the 10 drawings, is closed by the disk 15, which forms part of the cylinder head 3, and the cylinder head is also provided with a tubular extension 16 which forms a cylindrical chamber adapted to embrace the working 15 end of the liner 4.

The said tubular extension 16 of the cylinder head 3 is provided with an annular facing flange 18 which is adapted to be secured, by fastening devices 19, to the facing 20 flange 13 of the casing 2. The outer surface of the tubular extension 16 is provided with radial reinforcing ribs 20, as said tubular extension 16 takes the working load on the cylinder head disk 15.

25 The said tubular extension 16 is of sufficient length between the disk 15 and the facing flange 18, so that the disk 15 will be positioned a substantial distance from the facing flange 18, which flange forms the 30 point of rigid connection with the casing 2, to permit the metal of the tubular extension 16 to yield radially, due to expansion and contraction from changes in temperature, caused by the great heat of combustion, in 35 the working end of the cylinder, thus permitting the cylinder head disk 15 to expand and contract as it is not rigidly bolted directly to a fixed and unyieldable part, but is carried by the said tubular extension 16 40 containing sufficient length of metal to permit it to yield and take care of the expansion and contraction of the metal in the cylinder head and also in the cylinder head disk and thus eliminate the possibility of 45 the parts cracking.

The cylinder liner 4 is made in the form of a cylinder having an outer cylindrical member 22 formed thereon at the working end of the liner. The said cylindrical member 50 22 forms a shoulder 23 adapted to fit against the end of the casing 2 and said member 22 is of sufficient length to extend beyond the end of the casing 2 and occupy the portion of the cylinder head formed by 55 the tubular extension 16, so that the disk portion 15 of the cylinder head will close the end of the liner 4 and the said tubular extension 16 will embrace the member 22 of the liner 4. By means of the fastening 60 devices 19, which engage the annular flanges 18 and 13 on the cylinder head 3 and the casing 2, respectively, the liner 4 may be tightly clamped between the disk 15 of the cylinder head and the end of the casing 65 2, and the facing surface 17 provided upon

the said disk 15 will be thus tightly seated upon the end of the liner 4.

The registering of the liner 4 within the casing 2 is insured by means of the circular groove, or recess 25, formed in the end of 70 the casing 2, into which fits the cylindrical facing 26, formed on the member 22, and holds the liner 4 in proper alignment within the casing. The opposite end of the liner 4 is provided with a cylindrical facing surface 75 27, which registers with the cylindrical openings 29 and 30 formed in the portion 12 of the casing 2 and the adjacent portion of the frame 5. The central portion of the liner 4 is also provided with cylindrical 80 facing surfaces 32 and 33 which fit into the cylindrical opening 34 formed through the exhaust manifold 8 of the casing 2, which will be hereinafter more fully described.

The cylinder head 3 is held in alignment 85 and made to register with the liner 4 by means of the said cylindrical facing surface 26 formed upon the said cylindrical member 22 of the liner 4, which surface 26 extends a sufficient distance from the end 90 of the casing 2 to receive the cylindrical facing surface 36 formed within the tubular extension 16 of the cylinder head 3.

The working end of the liner 4 is cored to form a cooling jacket 38 between the main portion of the liner 4 and the said cylindrical member 22 forming part of the liner. Said cooling jacket 38 extends nearly to the end of the liner so that only the necessary thickness of metal at the end 39 remains 100 between the cooling jacket 38 and the cylinder head disk 15. The cylindrical member 22 and the wall of the main portion of the liner 4 are connected by small bosses 40, as shown in Fig. 7, to reinforce the parts of 105 the liner adjacent to the point of contact with the casing 2. Thus an unobstructed individual cooling jacket 38 is formed around the liner at the working end thereof which is subjected to the greatest amount 110 of heat. Said cooling jacket 38 in the liner registers with the cooling jacket 7 of the casing 2, so that the cooling agent may circulate freely from the inlet pipe 42 in the lower portion of the casing 2 and pass out 115 through the outlet pipe 43 located in the upper portion of the cooling jacket of the liner 4.

It will be seen that the working end of 120 the liner 4 and the cylinder head disk 15 may expand and contract radially and that the tubular extension 16 of the cylinder head 3 and the cylindrical member 22 of the liner 4 are of sufficient length and contain a sufficient amount of yieldable metal above 125 the face of the casing 2, to which the parts are rigidly bolted, to permit the parts to yield sufficiently to prevent the parts from cracking.

The exhaust manifold 8 forms part of the 130

casing 2 and consists of the annular walls 45 and 46 having cylindrical flanges 47 and 48 with concentric openings 34 formed therethrough to receive the facing surfaces 32 and 33 formed upon the enlarged cylindrical portion of the liner 4. Said annular walls 45 and 46 are connected by a longitudinal wall 49 which is eccentric with the liner 4, as shown in Fig. 4; thus forming an exhaust chamber 50 surrounding the liner 4 and connecting the exhaust ports 9, formed in the liner, with the exhaust outlet passage 51 formed in the casing 2. The exhaust manifold 8 is connected with the outer wall 10 of the casing 2 by radial ribs 52, as shown in Figs. 1, 2 and 4.

The exhaust manifold 8 is provided with hollow bosses 54, to strengthen the casing 2. Said bosses 54 extend between the walls 45 and 46 of the casing 2 and are located in the larger portion of the exhaust chamber 50, as shown in Fig. 4, and help to carry the working load, which is distributed through the casing 2, from the cylinder head 3, to the frame 5. Said bosses are made hollow for the free circulation of the cooling agent through them and they thus form part of the cooling jacket 7 of the casing 2 formed between the outer surface of the liner 4 and the wall 10 of the casing and between the wall 49 of the exhaust manifold 8 and the said wall 10 of the casing.

The liner 4 is provided with the above mentioned enlarged central portion 32 and 33 which extends through the exhaust manifold 8, and said central portion of the liner, between each of the exhaust ports 9, is provided with a cored passage 56 for the free circulation of the cooling agent.

The cylinder head 3 is constructed with a dome-shaped outer wall 60 which forms a cooling chamber 61, between the above mentioned disk 15 and said dome-shaped wall 60. At the highest point in the dome-shaped wall 60 is provided an aperture 62 for the cooling agent conveyer 63 adapted to direct the cooling agent to the hottest portion of the disk 15 and distribute the cooling agent over the entire surface of said disk. The dome-shaped wall 60 directs the cooling agent to the outlet formed around the said cooling agent conveyer 63 at the furthest point from the disk 15.

The cooling agent conveyer 63 is preferably made to form a unit with the fuel valve 65 (the fuel valve not being shown in the drawing). The fuel valve sleeve 65 extends through the dome-shaped wall 60 and its inner end fits into a seat formed around the fuel inlet opening 66 formed in the disk 15. The cooling agent conveyer 63 consists of a larger sleeve 67, which surrounds the fuel valve sleeve 65, and is provided with a bell shaped flange 68 at its end adjacent to the disk 15, and located a sufficient distance from the disk to permit the cooling agent to be directed against the disk and around the fuel valve sleeve 65. The fuel valve sleeve 65 and cooling agent conveyer sleeve 67 are formed upon a manifold-head 70. Said head 70 also is provided with a cylindrical wall 71 which fits into the opening 62 formed in the dome-shaped wall 60 and said wall 71 forms an annular outlet passage 72 for the cooling agent leading to the outlet pipe 73 connected with the said head 70. The inlet pipe 43 for the cooling agent is connected with a boss 75 in the head 70 through which boss a passage is formed communicating with the space formed within the cooling agent conveyer 67 and surrounding the fuel valve sleeve 65. It will be seen that by this novel arrangement the cooling agent enters the cylinder head through the inlet pipe 43, passes through the cooling agent conveyer 67 which surrounds and cools the fuel valve sleeve 65 and directs the cooling agent directly upon the disk 15, over which it is distributed radially and circulates throughout the entire cooling chamber 61 of the cylinder head.

The cylinder head is constructed with the valve-cage bosses 76 (the valve cages being omitted from the drawing), for the admission of air to the cylinder. The valve-cage bosses 76 are cored in the cylinder head casting and extend through the cooling chamber 61 in a line parallel with the length of the cylinder and thus reinforce the cylinder head 3 and help to resist the forces applied, by the working load in the cylinder, against the disk 15, to which latter the bosses are directly connected and are held under compression during the working load in the cylinder. By this construction I eliminate all side inlet and outlet connections through the cooling chamber of the cylinder head, which said side inlet and outlet connections frequently crack due to the compression forces being applied at right angles to the length of the bosses forming the side connections through the cylinder head.

Having thus described my invention, I claim and desire to secure by Letters Patent:

1. An engine cylinder comprising a casing, a liner mounted within the casing and having the working end of the liner extending a substantial distance beyond the end of the casing to permit the working end of the liner to have sufficient flexibility for radial expansion and contraction, a cylinder head having a disk adapted to rest against and close the end of the liner, a tubular extension formed upon the cylinder head adapted to embrace the working end of the liner, and fastening devices for securing said extension of the head upon the end of the casing.

2. An engine cylinder comprising a casing, a cylinder liner mounted within the casing and having the working end thereof extending a substantial distance beyond the 5 end of the casing, said extension having a chamber formed therein adapted to contain a cooling agent, a cylinder head adapted to close the working end of the liner positioned upon the extreme end surface of the liner 10 and adapted to expand radially thereon, fastening devices for securing the cylinder head to the end of the casing, and said fastening devices being positioned outside of and free from said extension of the liner.
- 15 3. An engine cylinder comprising a casing, a cylinder liner mounted within the casing and having the working end thereof extending a substantial distance beyond the end of the casing, said extension having a 20 chamber formed therein adapted to contain a cooling agent, a cylinder head having a disk adapted to be clamped against the end surface of the liner and adapted to expand radially thereon, said extension upon the 25 liner having a solid wall adapted to seal said chamber formed therein at the end of the liner adjacent to said disk, and fastening devices adapted for securing the cylinder head to the casing positioned outside of and 30 free from the extension of the liner.
4. An engine cylinder comprising a casing, a cylinder liner mounted within the casing and having the working end thereof extending a substantial distance beyond the 35 end of the casing, said extension having a chamber formed therein adapted to contain a cooling agent, a shoulder upon the liner adapted to rest against the end of the casing, said casing forming a cooling agent chamber surrounding a portion of the liner and 40 communicating with the extension of the liner forming said chamber within said extension, a cylinder head having a seat upon the end of the extension of the liner and a 45 flange upon the cylinder head adapted to be clamped against the end of the casing in spaced relation thereto and adapted to form an open joint between the cylinder head flange and the end of the casing for the 50 escape of leakage of the cooling agent and combustion gases.
5. An engine cylinder comprising a casing, a cylinder liner mounted within the casing and having one end thereof extending a substantial distance beyond the end of the casing, an outer cylindrical member formed upon the said end of the liner and extending between the said end of the liner and the end of the casing, said cylindrical 55 member of the liner forming a shoulder at its inner end adapted to bear against the end of the casing, a cylinder head adapted to close the said end of the liner, a tubular extension formed upon the cylinder head 60 adapted to embrace the end of the cylinder 65

liner, and fastening devices for clamping the tubular extension of the cylinder head to the end of the casing.

6. An engine cylinder comprising a casing, a cylinder liner mounted within the casing and having one end thereof extending a substantial distance beyond the end of the casing, an outer cylindrical member formed upon the end of the liner extending beyond the end of the casing, said liner having an 70 annular space formed therein between the main portion thereof and the said cylindrical member thereof for the circulation of a cooling agent around the portion of the liner extending beyond the casing, a cylinder 75 head adapted to close the end of the liner, a tubular extension formed upon the cylinder head adapted to embrace the portion of the liner extending beyond the casing, and fastening devices for clamping the tubular 80 extension of the cylinder head to the end of the casing.

7. An engine cylinder comprising a casing, a cylinder liner mounted within the casing and having one end thereof extending a substantial distance beyond the end of the casing, an outer cylindrical member formed upon the end of the liner extending beyond the end of the casing, said liner having an 85 annular space formed therein between the main portion thereof and the said cylindrical member thereof forming a cooling agent jacket, said outer cylindrical member of the liner forming a shoulder adapted to bear against the end of the casing, reinforcing bosses connecting the main portion of the liner with the outer cylindrical member thereof, said bosses located adjacent to the said shoulder, a cylinder head adapted to embrace the end of the liner extending beyond the casing, and means for securing the cylinder head to the casing.

8. An engine cylinder comprising a casing, a cylinder liner mounted within the casing and having one end thereof extending a substantial distance beyond the end of the casing, an outer cylindrical member formed upon the end of the liner extending beyond the end of the casing, a cooling agent jacket formed in the liner between the main portion thereof and the said outer cylindrical member thereof, said outer cylindrical member of the liner adapted to rest against the end of the casing, said casing forming a cooling agent jacket between the liner and the wall of the casing and adapted to register with the said annular cooling agent jacket of the liner extending beyond the end of the casing, a cylinder head adapted to close the end of the liner, and a tubular extension upon the cylinder head adapted to embrace the end of the liner and secure the liner to the casing.

9. An engine cylinder comprising a casing, a cylinder liner mounted within the cas-

ing and having one end thereof extending a substantial distance beyond the end of the casing, an outer cylindrical member formed upon the end of the liner extending beyond the end of the casing, said cylindrical member forming a shoulder adapted to register with and rest against the end of the casing, a cylinder head having a disk to close the end of the liner, a tubular extension upon the cylinder head adapted to embrace the end of the cylinder liner, an annular flange upon the end of the said tubular extension for securing the cylinder head to the casing and for clamping the liner upon the casing, and said tubular extension of the cylinder head and the said cylindrical member of the liner having sufficient length of material extending beyond the end of the casing to permit of radial flexibility of the liner and cylinder head.

10. An engine comprising a casing, a liner mounted within the casing and having the working end free from contact with the casing whereby the liner at the hottest part thereof is free to expand and contract radially, a facing surface formed upon the said end of the liner, a head having a facing surface adapted to be positioned against the said facing surface of the liner, and close the working end of the liner, and fastening devices for securing the head to the casing on a plane located a substantial distance from the plane of contact with the end of the liner to permit the head to yield radially in the plane where the head impinges against the end of the liner.

11. An engine having a cylinder and a cylinder head, said cylinder head comprising a disk adapted to close the end of the cylinder, an outer wall in the cylinder head forming a chamber for a cooling agent between said outer wall and said disk, a detachable fuel valve sleeve extending through an aperture formed in said outer wall and communicating with an aperture formed in said disk, a supply pipe surrounding the fuel valve sleeve for conveying a cooling agent throughout the length of said sleeve, said supply pipe having its inner end positioned in spaced relation to the disk thus forming an annular orifice for radially distributing the cooling agent over the disk, and said outer wall having an outlet passage-way formed therein for the cooling agent, said outlet passage-way positioned in the outer wall adjacent to the supply pipe.

12. An engine having a cylinder and a cylinder head, said cylinder head comprising a disk adapted to close the cylinder, a dome

shaped outer wall joined to the periphery of the disk and forming a chamber for a cooling agent, a fuel valve sleeve extending through an aperture formed in the dome shaped wall and communicating with an aperture formed in the disk, a cooling agent supply pipe surrounding the fuel valve sleeve having its inner end terminating adjacent to the disk to form an annular orifice surrounding the fuel valve sleeve through which the cooling agent may be forced radially over the surface of the disk towards the curved sides of the dome shaped wall, said dome shaped wall having an outlet formed therein adjacent to the supply pipe towards which outlet the curved dome shaped wall directs the cooling agent and guides it to said outlet.

13. An engine having a cylinder and a cylinder head, said cylinder head comprising a disk adapted to close the cylinder, a dome shaped outer wall joined to the periphery of the disk and forming a chamber for a cooling agent, a fuel valve sleeve extending through an aperture formed in the dome shaped wall and communicating with an aperture formed in the disk, a cooling agent supply pipe surrounding the fuel valve sleeve having its inner end terminating adjacent to the disk to form an annular orifice surrounding the fuel valve sleeve through which the cooling agent may be forced radially over the surface of the disk towards the curved sides of the dome shaped wall, an outlet pipe concentrically mounted in relation to the supply pipe and to the fuel valve sleeve, said outlet pipe forming an annular discharge outlet for the cooling agent from the said chamber.

14. An engine comprising a cylinder forming a combustion space, a cylinder head having a chamber forming a cooling agent jacket, a disk portion in the cylinder head separating the said chamber from said combustion space, a fuel valve sleeve extending through the chamber of the cylinder head, a larger sleeve embracing the fuel valve sleeve forming a cooling agent conveyer around the fuel valve sleeve and extending adjacent to said disk, a manifold-head carrying the fuel valve sleeve and the said larger sleeve, said manifold-head adapted to be detachably secured to the cylinder head, and said manifold-head having inlet and outlet passages formed therein for the circulation of the cooling agent through the cylinder head chamber.

In testimony whereof I affix my signature.

HUBERT C. VERHEY.
